UNITED STATES PATENT OFFICE.

WILLIAM H. WILSHIRE, OF LOS ANGELES, CALIFORNIA.

FINGER RECOIL PAD.

Application filed November 10, 1926. Serial No. 147,490.

This invention relates to a new and useful device adapted for attachment to the trigger guard of any firearm, and its object is to protect the finger of the shooter from a bruise upon recoil of the firearm when the same is discharged; and to provide a device of this character which may be attached to any trigger guard without alteration thereof or of the firearm.

10 Other objects are to provide a recoil pad having the characteristics of simplicity of construction, efficiency in use, and ease of attachment.

In any gun or firearm, except those of ins- 15 consequential power and caliber, the recoil is often sufficient to bruise the trigger hand of the shooter, and especially the fingers that are adjacent to the trigger guard of the gun or firearm.

20 To avoid this objection, I have provided a recoil pad adapted to be clamped to the trigger guard and to efficiently protect the fingers adjacent to the trigger guard, and consisting of a backing member adapted to be 25 mounted on the rear face of the trigger guard, clamp elements arranged to secure the backing member to the trigger guard, and a pad of elastic and yieldable material secured to the backing member.

30 The accompanying drawings illustrate an embodiment of the device which I have so far found to be the most practical in use, but it is evident that various changes, modifications and variations might be resorted to 35 without departing from the spirit and scope of my invention and hence I do not wish to be limited to the exact disclosures hereof.

In the drawings, Figure 1 is a fragmentary and side elevation of a firearm, showing 40 the trigger guard provided with my improved finger recoil pad. Fig. 2 is a side and detail view of the finger recoil pad detached from the trigger guard. Fig. 3 is a plan view of the clamping element before 45 bending to correspond with the trigger guard. Fig. 4 is a transverse section through the trigger guard and the recoil pad. Fig. 5 is a fragmentary and detail view of a firearm showing a modified form 50 of my improved device attached to the trigger guard. Fig. 6 is a transverse section of the trigger guard and recoil pad shown in Fig. 5. Fig. 7 is a transverse section of the recoil pad with one of the clamping elements 55 detached therefrom. Fig. 8 is a side and detail view of a detached clamping element.

Fig. 9 is a side and detail view of the recoil pad as shown in Figs. 5, 6, 7 and 8, but with the clamping elements detached.

Referring to the drawings in detail, the 60 clamp member 11, consists of a thin sheet metal element having prongs 12, adapted to be clamped or bent upon the trigger guard 13, and having alternate prongs 14, which are adapted to be clamped or bent upon the backing piece 15. In the present instance, I make the backing piece 15, from hard or other rubber material, and I securely mount thereon the elastic and yieldable pad 16, which in the present instance, is made from 70 sponge rubber, and which is cemented or vulcanized to the backing piece. The clamp member 11 has an extension 17, which is bent upon the lower end of pad 16, and thereby protects the same. In the present instance, 75 I construct the clamp member 11, from thin copper sheets of metal, but any metal of similar quality may be considered the equivalent thereof.

In the modified form shown in Figs. 5, 80 6, 7, 8 and 9, I provide a thin metal strip 18 adapted to be positioned upon the rear face of trigger guard 19, and having mounted thereon the backing piece 20, which has a soft sponge rubber pad 21, cemented thereto. 85 The metal clamping elements 22 and 23, are positioned one on each side of member 20, and are provided with prongs 24, adapted to engage with the trigger guard, and provided with clamping screws 25, as shown.

90 In use, as the firearm recoils, the soft pad 16 or 21, as the case may be, yields to the pressure of the finger adjacent thereto. Firearms of heavy recoil may therefore be used for a number of shots without injury 95 to the fingers of the shooter.

I have disclosed and described herein a finger recoil pad embodying my invention applied to a certain trigger guard, but I do not limit myself to the specific shape of the 100 parts, nor to the exact positioning disclosed herein.

What is claimed is:

1. A finger recoil pad, comprising a strip of metal adapted to abut against the rear 105 face of the trigger guard, a backing piece fixed to the metal strip, a pad of yieldable material fixed to the backing piece, clamping elements, one positioned on each side of the backing piece and engaging with the 110 trigger guard, and clamping screws extending through the backing piece and clamping

elements, and binding the clamping elements to the trigger guard.

2. A finger recoil pad, comprising a metal strip adapted to abut against the rear face 5 of a trigger guard, a backing piece fixed to the metal strip, said strip and backing piece being narrower than the trigger guard, a pad of elastic and yieldable material fixed to the backing piece, clamp members, one 10 positioned on each side of the backing piece, prongs on the clamp members adapted to engage with the trigger guard, and clamping screws extending through the clamp members and backing piece, and serving to 15 force the clamping members in engagement with the trigger guard.

3. A finger recoil pad, comprising a metal strip adapted to abut against the rear face of a trigger guard and conforming with the 20 contour thereof, a backing piece fixed to the metal strip, a pad of elastic and yieldable material fixed to the backing piece, a tongue on the metal strip extending under the elastic pad, and clamping elements carried by 25 the backing piece and adapted to engage with the trigger guard in clamping position.

4. In a finger recoil pad for firearms, the

combination with a backing piece of non-elastic material, of a yieldable and elastic pad mounted on and fixed to the backing 30 piece, a metal strip on the front face of the backing piece and conforming in contour with the rear face of the trigger guard, clamping members one positioned on each side of the backing piece, prongs on each 35 clamping member adapted to engage with the trigger guard in clamping position, and screws extending through the backing piece and through the clamping members and serving to force the clamping members into 40 rigid engagement with the trigger guard in clamping position.

5. In a finger recoil pad for firearms, the combination with a backing piece adapted to be positioned upon the rear face of the trigger guard, of a pad of elastic material 45 mounted on the backing piece, and a clamping member having a series of prongs in engagement with the backing piece, and another series of prongs adapted to engage 50 with the trigger guard in clamping position.

In testimony whereof, I hereunto affix my signature.

WILLIAM H. WILSHIRE.
